(57) **CLAIM**

The ornamental design for a seat belt cover, as shown and described.

DESCRIPTION

FIG. 1 is a rear perspective view of a seat belt cover showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front elevational view of a seat belt cover thereof.

The broken line showing of the hook and loop fastener material in FIGS. 1, 6, and 7 and the safety strap and belt in FIG. 8 is for illustrative purposes only and forms no part of the claimed design.

1 Claim, 4 Drawing Sheets
